Inventor

ROBERT McLAUGHLIN.

UNITED STATES PATENT OFFICE.

ROBERT McLAUGHLIN, OF MONMOUTH, ILLINOIS, ASSIGNOR OF ONE-HALF TO A. G. PATTON, OF MONMOUTH, ILLINOIS.

FARM-GATE HINGE.

1,421,794.

Specification of Letters Patent.

Patented July 4, 1922.

Application filed November 15, 1920. Serial No. 424,151.

To all whom it may concern:

Be it known that I, ROBERT McLAUGHLIN, a citizen of the United States, and a resident of the city of Monmouth, in the county of 5 Warren and State of Illinois, have invented certain new and useful Improvements in a Farm-Gate Hinge; and I do hereby declare that the following is a full, clear, and exact 10 description of the same, reference being had to the accompanying drawings, and to the numerals of reference marked thereon, which form a part of this specification.

My invention relates more particularly to a hinge construction for a farm gate and 15 comprises means for properly bracing the members that comprise the hinge.

It is an object of this invention to provide a hinge construction that is strong, durable and braced against shearing stresses so as 20 to eliminate sagging of the gate.

Other and further important objects of this invention will be apparent from the disclosures in the specification and drawings.

My invention (in a preferred form) is 25 illustrated in the drawings and hereinafter more fully described.

In the drawings:

Figure 1 is a side elevation of a gate suspended by a hinge construction involving 30 my invention.

Figure 2 is a top plan view of a section of the gate upon an enlarged scale.

Figure 3 is a fragmentary top plan view of the hinge connection upon an enlarged 35 scale.

Figure 4 is a fragmentary top plan view of a modified form of hinge construction.

Figure 5 is a fragmentary top plan view of a modified form of hinge construction.

40 Figure 6 is a section on the line 6—6 of Figure 5.

As shown on the drawings:

In the different figures of the drawings, similar features are denoted by similar 45 reference characters.

In Figure 1, I have illustrated the application of my invention to a farm gate which is usually constructed of a number of spaced boards and transverse struts secured to the 50 boards, and as these gates are generally long and heavy, it has always been a difficult problem to secure a simple gate hinge properly braced against sagging of the gate and shearing of the bolts that secure the 55 hinges to the gate. I have discovered that

by extending the hinge members and bracing them against an angled strut, the tendency of the gate to sag will be practically eliminated and the stresses will be so distributed that the usual strain on the gate 60 hinges will be greatly diminished. And to accomplish this purpose, I provide the long metal hinge members or straps 1 and 2 substantially equal to the depth of the gate as shown in Fig. 1, which are composed of an 65 integral structure so constructed as to provide a loop 2 designed to fit over a hinge anchor 3 and bent to provide abutments 4 contacting with the rear end of a board. Adjacent the rear ends of the boards that 70 comprise the gate are a pair of plain struts 5 and spaced forwardly from these are a second pair of struts 6 which may consist of angle irons. The hinge members 1 and 2 extend forwardly one on each side of the 75 gate and over the first pair of struts to which they are secured and under the second pair of struts 6 to which they are likewise secured. At intermediate points between these struts, the hinge members 1 and 2 are also 80 secured to the upper board of the gate by means of bolts or the like. Diagonal brace members 7 extend from these hinge members 1 and 2 to the struts 6, being firmly secured to each and to the boards of the gate. 85 The upper and lower hinges are identical in structure, and together with the struts 5 and 6 form a square or rectangular trussed frame that supports the wooden gate which abuts against the abutments 4, thus reducing the 90 shear on the bolts that secure the hinge members, especially the lower members, to the gate.

In Figure 4, I have illustrated a modified form of hinge which may be used in certain 95 instances. The construction differs from the one above in that the hinge members or straps 8 and 9 are bolted or secured in overlapping relation to the same side of the gate to define a loop 10 at the rear of the gate 100 adapted to receive the gate anchoring bolt 3.

Figures 5 and 6 illustrate a further modification of my invention in which the hinge members 11 and 12 comprise an integral structure formed and attached as the hinge 105 illustrated in Figures 1, 2 and 3, the only difference residing in the form or shape of the hinge which consists of an angle member having the flanges 13 and 14 which produce a very rigid construction and prevent 110

distortion or bending of the hinge when in use.

It will accordingly be observed that I have invented a novel hinge construction that is 5 cheap, economical and durable, that is strongly braced against shearing stresses and strains and that forms with the struts a metal frame that supports the gate, in connection with which, it should be particularly 10 noted that the strain produced by the gate is well distributed over this metal frame structure and there is not the liability for the hinges to become loose or the bolt holes in the wooden gate to become enlarged so 15 that the gate can sag, as would be the case if the hinge members were only secured to the wooden gate.

I am aware that numerous details of construction may be varied through a wide 20 range without departing from the principles of this invention, and I therefore do not purpose limiting the patent granted otherwise than necessitated by the prior art.

I claim as my invention:

25 1. The combination with a gate, upper

and lower hinges connected thereto and extending forward a distance equal to approximately the depth of said gate, a pair of vertical struts secured to the gate near the rear end thereof, a second pair of struts secured to said gate at the forward end of said 30 hinges, said hinges being connected to said struts, and members bracing said hinges with one pair of struts whereby a rectangular trussed frame is provided.

2. In a farm gate structure, the combination with a plurality of pairs of spaced struts, upper and lower hinge members connected to said struts and extending beyond the gate in looped formation, and braces connecting said hinge members to one pair of 40 struts.

In testimony whereof, I have hereunto subscribed my name in the presence of two subscribing witnesses.

ROBERT McLAUGHLIN.
